Frank A. Cutler,
ATTORNEY.*

UNITED STATES PATENT OFFICE.

GEORGE L. BIDWELL, OF RIEGELSVILLE, PENNSYLVANIA.

BEATER-ROLL.

1,362,219.

Specification of Letters Patent. Patented Dec. 14, 1920.

Application filed March 1, 1920. Serial No. 362,327.

To all whom it may concern:

Be it known that I, GEORGE L. BIDWELL, a citizen of the United States of America, and a resident of Riegelsville, in the county 5 of Bucks and State of Pennsylvania, have invented a new and useful Beater-Roll, of which the following is a specification.

My invention relates to improvement in beater rolls which are used in connection 10 with the bed-plates or bed-knives in that type of beater engines known as Hollander engines, and consists of a shaft, a plurality of spiders secured to said shaft, and segmental plates or segments secured to said 15 spiders, said segments having integral bars which constitute blades or knives and are adapted to operate in connection or to co-operate with a bed-plate or bed-knife to reduce the stock, the joints between said segments being filled, together with such other 20 parts and members as may be necessary or desirable in order to render the roll complete, all as hereinafter set forth.

Inasmuch as it is necessary that the beater 25 roll be water-tight, and capable of withstanding heat and the corrosive action of the cooking and bleaching solutions to which it is subjected, and the abrasive action or wear incident to the cutting action thereof, 30 in conjunction or co-operation with the aforesaid bed-knife, on the hard stock in connection with which this roll is particularly designed for use, the joints between the segments of said roll are sealed with lead, said 35 segments are preferably made of manganese steel, which is very hard and durable, not appreciably affected by heat, that is to say, by the heat from a Hollander engine, and well able to stand up under and endure the 40 corrosive and abrasive actions just referred to, and the ends of the beater are tightly closed, all in the manner presently to be more fully explained herein.

The primary object of my invention is 45 to produce a beater roll, for a Hollander engine, which, while sectional, has no wood in its construction, but is made of metal throughout, possesses great powers of strength and endurance, is water-tight so 50 that none of the contents of the engine, which is equipped with this roll, can find its way into the interior of the roll, and can be subjected to any practical degree of temperature without being affected.

55 A further object is to provide such a beater

roll for a Hollander engine that is especially adapted for use in carrying into effect my new process of making pulp for paper, which pulp is made out of hard stock, such as rags, burlap, gunny, rope, jute, hemp, and sisal, fed in large pieces to said engine, an application, Serial No. 362,325, for Letters Patent of the United States on said process being filed of even date herewith.

Other objects and advantages will appear 65 in the course of the following description.

I attain the objects and secure the advantages of my invention by the means illustrated in the accompanying drawings, in 70

Figure 1 is an end elevation of a beater roll which embodies a practical form of my invention; Fig. 2, a cross section through said roll; Fig. 3, an approximately central, longitudinal section through said roll, and, 75 Fig. 4, an enlarged detail of one of the joints between two of the segmental plates which form the cylinder of the roll.

Similar reference numerals designate similar parts throughout the several views.

Referring to the drawings it will be observed that the beater roll therein illustrated comprises, with an ordinary beater-roll spindle or shaft, such as is found in a Hollander engine, two end spiders 2 and 80 an intermediate spider 3 mounted on said shaft and keyed thereto, as represented at 4, a plurality of segments 5 secured by bolts 6 to the peripheries of said spiders, said segments having exterior, integral bars forming 85 knives 7 that extend longitudinally of the segments, and plates or heads 8, and so-called bangers 9.

The spiders 2 and 3 are similar to wheels having hubs, spokes, and rims, and the spider 3 differs from the other two only in that the intermediate portions of the spokes in the middle spider are narrower than corresponding portions of the spokes of the end spiders, the outer sides of the latter spokes 95 being flush with the outer ends of the hubs and the outer edges of the rims of said end spiders. The entire outer surfaces of the end spiders 2 can, therefore, be utilized as abutments for the end plates 6, whereby the 100 latter may be comparatively thin, and the structure is rendered stiffer and stronger.

The segments 5 have lapped joints 10 at their longitudinal edges, and these joints are filled with either sheet-lead or melted lead 110

run into said joints or between the lapped portions of said segments, as represented at 12 in Fig. 4, so that the hollow cylinder formed by the segments is water-tight. This hollow cylinder fits on to the peripheries of the spiders 2 and 3 and is secured thereon by means of the bolts 6, each segment 5 being by preference individually bolted to said spiders. The segments 5 project at each end beyond the spider 2 at that end. The knives 7 are equidistant from each other, and are the members which, in conjunction with the stationary or fixed knife of the Hollander engine in which the beater roll is mounted, cut and reduce the hard stock.

The ends of the beater roll are tightly closed by means of the plates 8. Said plates are made in sections, two for each end of the roll, and they fit tightly against the end spiders 2, within the extended rims of the segmental cylinder, and around the shaft 1, being bolted at 11 to said spiders.

The construction above described constitutes or forms a beater roll that possesses all of the advantages hereinbefore pointed out, including the special adaptability for use in my new process of making pulp from hard stock.

The bangers 9 are on the outer surfaces of the plates 8, and they are provided for the purpose of maintaining a clearance at each end of the beater roll between such end and the adjacent wall of the Hollander engine, in which said roll is located. These bangers also cut through the semi-fluid mass in the engine and prevent the same from accumulating between the ends of the roll and the adjacent sides or walls of the engine. Said bangers are arcuate in shape, and each may consist of two ribs made integral with the plates 8 at each end of the roll, and arranged so that their inner ends abut, or each might consist of a separate piece or pieces bolted or otherwise secured to said plates.

In practice the beater roll is mounted in the Hollander engine, adjusted to the bed-plate or knife therein, and operated in practically the same manner as the old type of beater roll.

More or less change in minor details of construction of this roll may be made without departing from the spirit of my invention or exceeding the scope of what is claimed.

What I claim as my invention, and desire to secure by Letters Patent, is—

1. As an improved article of manufacture, a beater roll, for Hollander engines, comprising a shaft, spiders mounted on said shaft, and a hollow cylinder mounted on said spiders, said cylinder consisting of a

plurality of segments having filled joints, and provided with integral knives.

2. As an improved article of manufacture, 65 a beater roll, for Hollander engines, comprising a shaft, spiders mounted on said shaft, and a hollow cylinder mounted on said spiders, said cylinder consisting of a plurality of segments having lapped joints, 70 and provided with integral knives.

3. As an improved article of manufacture, 75 a beater roll, for Hollander engines, comprising a shaft, spiders mounted on said shaft, and a hollow cylinder mounted on said spiders, said cylinders consisting of a plurality of segments having lapped and filled joints, and provided with integral knives.

4. As an improved article of manufacture, 80 a beater roll, for Hollander engines, comprising a shaft, spiders mounted on said shaft, and a plurality of segments mounted on said spiders and bolted thereto, said segments forming a hollow cylinder, and being 85 provided with integral knives.

5. As an improved article of manufacture, 90 a beater roll, for Hollander engines, comprising a shaft, spiders mounted on said shaft, and a plurality of segments mounted on said spiders and bolted thereto, said segments forming a hollow cylinder with lapped joints, and being provided with integral knives.

6. As an improved article of manufacture, 95 a beater roll, for Hollander engines, comprising a shaft, spiders mounted on such shaft, and a plurality of segments mounted on said spiders and bolted thereto, said segments being provided with integral knives, 100 and the joints between said segments being filled.

7. As an improved article of manufacture, 105 a beater roll, for Hollander engines, comprising a shaft, spiders mounted on said shaft, and a plurality of segments mounted on said spiders and bolted thereto, said segments forming a hollow cylinder with lapped joints, and being provided with integral knives, and said joints being filled. 110

8. The combination, in a beater roll, for Hollander engines, with a shaft, spiders mounted on said shaft, and a plurality of segments mounted on said spiders and bolted thereto, said segments forming a hollow cylinder with lapped joints, and being provided with integral knives, and said joints being filled, of plates fitting around said shaft, within the rims of said cylinder, to close the ends of the cylinder. 115
